HIS ATTORNEY

UNITED STATES PATENT OFFICE

1,953,095

DETACHABLE BIT

John B. Baker, Canton, Ohio, assignor to The
Timken Roller Bearing Company, Canton,
Ohio, a corporation of Ohio

Application July 18, 1931, Serial No. 551,685

3 Claims. (Cl. 255—64)

My invention relates to detachable bit constructions and has for its principal objects a screw thread arrangement therefor which will not bind and which is capable of withstanding the heavy 5 shocks resulting from drilling operations. Great difficulty has been experienced in finding thread constructions suitable for such use, most threads soon becoming jammed so as to prevent disassembly of the parts, or breaking off under the 10 heavy shocks and stresses. The thread constructions of the present invention satisfactorily meet the requirements. The invention consists in providing the rear faces of at least one thread member with a substantially straight profile. It further 15 consists in the detachable bit construction and in the parts and combinations and arrangements of parts hereinafter described and claimed.

In the accompanying drawing,

Fig. 1 is an elevation, partly in longitudinal 20 section, of a detachable bit construction whose threaded connections embody my invention.

Fig. 2 is a view similar to Fig. 1 of the parts in detached position, the metal coupling member only being shown in longitudinal section; and 25 Figs. 3, 4, 5 and 6 are detail sectional views of several modifications of screw threads embodying my invention.

The drawing illustrates my invention as embodied in a detachable bit construction including 30 a drill rod 1 having a tapering threaded end portion 2, a bit member 3 having a tapering threaded shank 4 and a hollow coupling member 5 having tapering threaded bores to cooperate with said shank 4 and with said drill rod 1. According to 35 my invention, the front faces 6 of all of the threads are rather short and are disposed substantially flatwise to the end thrust to which they are subjected. The rear faces of all of the threads (indicated generally by the letter A) are com- 40 paratively long, making a comparatively small angle with the axis of the drill rod; and the rear face of at least one thread is convexly curved endwise. A space 7 is left at the crest of each thread.

45 In the construction shown in Fig. 3, the rear face 8 of the thread of the inner member (drill rod 1 or bit shank 4) is convexly curved endwise so to have a convex section or profile. The rear face 9 of the thread of the coupling member 5 is substantially straight in profile.

In the construction shown in Fig. 4, the rear face 19 of the thread of the coupling member 5 is convexly curved, the rear face 18 of the thread of the inner member being substantially straight.

55 In the construction shown in Fig. 5, the rear

faces 28 and 29 of both sets of threads are convexly curved but are provided with straight zones 25 at their middle portions.

In the construction shown in Fig. 6, the rear faces 38 and 39 of both inner and outer members 60 are convexly curved.

The convex curvature of one thread cooperating with the construction of the other thread whereby there is limited contact between the two threads makes the threads cooperate together 65 easily and prevents jamming of the threads. Heavy shock and wear may flatten said curves; but extraordinarily long service is required to cause sufficient flattening of the curves to permit the threads to bind. Previous curved thread constructions have included mating, closely fitting 70 continuous curves on both thread members; and the important advantages of the present construction depend upon the absence of such mating thread surfaces.

What I claim is:

1. A detachable bit construction comprising an internally threaded coupling member and externally threaded drill rod and bit shank, the front faces of all of said threads being comparatively 80 short and disposed substantially flatwise with respect to end thrust and the rear faces of said threads being rather long, the rear face of one of each contacting pair of said threads being convexly curved endwise.

2. A detachable bit construction comprising an internally threaded coupling member and externally threaded drill rod and bit shank, the front faces of all of said threads being comparatively 90 short and disposed substantially flatwise with respect to end thrust and the rear faces of said thread being rather long, the rear faces of the threads of said coupling member being substantially straight in profile and the cooperating rear faces of the threads of said drill rod and of said 95 bit shank being convexly curved in profile.

3. A detachable bit construction comprising an internally threaded member and an externally threaded member, the front faces of said threads being comparatively short and disposed substantially flatwise with respect to end thrust and the rear faces of said threads being rather long, the rear face of one of each contacting pair of said threads being convexly curved endwise.

JOHN B. BAKER. 105
